Primary Examiner — Erich G Herbermann*Assistant Examiner* — Altaira J Swangin(74) *Attorney, Agent, or Firm* — Crestron Electronics, Inc.(57) **CLAIM**

The ornamental design for a display panel with tabletop mount, as shown and described.

DESCRIPTION

FIG. 1 is a top perspective view of a display panel with tabletop mount;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

In the drawings, the broken lines and the areas within the broken lines illustrate portions of the display panel with tabletop mount that form no part of the claimed design.
